BY Chas B. Mann
ATTORNEY.

UNITED STATES PATENT OFFICE.

CHARLES SPIESS, OF BALTIMORE, MARYLAND.

DUMPING-CART.

SPECIFICATION forming part of Letters Patent No. 440,580, dated November 11, 1890.

Application filed July 18, 1890. Serial No. 359,236. (No model.)

To all whom it may concern:

Be it known that I, CHARLES SPIESS, a citizen of the United States, residing at Baltimore, in the State of Maryland, have invented 5 certain new and useful Improvements in Upsetting Dumping-Carts, of which the following is a specification.

This invention relates to an upsetting dumping-cart for hauling various materials.

10 The invention is shown in the accompanying drawings, in which—

Figure 1 is a side elevation of the cart, showing the body in the upright normal position. Fig. 2 is a front elevation of the same. Fig. 15 3 is a side elevation showing the body in the upset or dumping position. Fig. 4 shows two views of one of the rollers that act when the body is upset. Fig. 5 shows two views of the spring door-catch.

20 The axle A is of that form which are termed "crank-axles"—that is, the middle of the axle a, on which the body rests, is on a much lower plane than the arms a' of the axle.

The wheels B are of ordinary construction, 25 and the body or box C occupies the space between the two axle-arms a'. This box is slightly tapering, being smaller at the bottom b than at the top. At the top sides it has a flaring or inclined side-board d and at the 30 front a door e, secured to the bottom by hinges f, and when closed held at each side by a spring-catch g, which is made fast to the sides of the body-box. For some purposes or some material in loading or unloading this front 35 door is desirable.

A caster-wheel H is secured to the bottom at the rear end of the box, and a suitable handle-bar I is made fast to the rear of the box near the top. A grip loop-handle j is also at 40 the rear near the bottom to assist in upsetting and restoring the box or body to its upright position. Another loop-handle k is on the exterior of the bottom of the box to assist after the box has been dumped in dragging 45 the cart back to relieve the box of the load.

The front door e extends only part way up the front of the body-box, and the sides l of

said box from the top of the door to and including the flaring side-boards d have inclined front edges l', which when the box has been 50 upset take position above the ground or the floor whereon the cart may be standing. Attached to the box sides at these inclined front edges l' are rollers m, one roller at each side. These rollers m project beyond the inclined 55 front edge of the body-box, and when the box has been upset, as in Fig. 3, said rollers come in contact with the floor at a point sufficiently in front of that where the wheels B are in contact with the floor to support the body-box 60 and keep it from dragging on the floor. These rollers m on the inclined front edges are thus a very useful adjunct to the cart-body.

This cart is light-running, is easily dumped, and may be drawn or run by hand or by animals.

The cart is adapted for many uses which are unnecessary to enumerate here.

Having described my invention, I claim—

1. A dumping-cart having in combination 70 a crank-axle A, a body-box having flaring side-boards at the top and said box occupying space between the two arms of the crank-axle, a caster-wheel secured to the body-box, and a hand-bar I.

2. A dumping-cart having in combination 75 a crank-axle, a body-box having a front door e, hinged to the bottom and occupying the space between the two arms of the crank-axle, and a caster-wheel secured to the body-box 80 at the rear.

3. A dumping-cart having in combination 85 a crank-axle A, a body-box having sides l, which have inclined front edges l', a roller m, secured to and projecting beyond each of said inclined front edges, and a caster-wheel H, secured to the body-box at the rear.

In testimony whereof I affix my signature in the presence of two witnesses.

CHARLES SPIESS.
